United States Patent

Des. 237,050
Patented Oct. 7, 1975

237,050

PACKAGING CONTAINER FOR GLASSWARE OR THE LIKE

Robert L. Forté, Lancaster, Ohio, assignor to
Anchor Hocking Corporation

Filed Mar. 20, 1974, Ser. No. 452,723

Term of patent 14 years

Int. Cl. D9—03

U.S. Cl. D9—176

FIG. 1

FIG. 2

FIG. 3

FIG. 1 is a top perspective view of a packaging container for glassware or the like showing my new design;

FIG. 2 is an end elevational view, the opposite end being the same in appearance; and

FIG. 3 is a side elevational view, the opposite side being the same in appearance.

The bottom is plain and unornamented like the top.

I claim:

The ornamental design for a packaging container for glassware or the like, substantially as shown and described.
